UNITED STATES PATENT OFFICE.

ISAAC EDWARD YORK, OF WATERFORD, ONTARIO, CANADA.

STOCKING-STRETCHING DEVICE.

1,022,457.

Specification of Letters Patent.

Patented Apr. 9, 1912.

Application filed October 5, 1911. Serial No. 652,992.

To all whom it may concern:

Be it known that I, ISAAC EDWARD YORK, of the town of Waterford, in the county of Norfolk, in the Province of Ontario, Canada, have invented certain new and useful Improvements in Stocking-Stretching Devices, of which the following is the specification.

My invention relates to improvements in a stocking stretching device and the object of the invention is to devise a simple, cheap, readily adjustable device which may be inserted in the foot of a damp stocking so that as the stocking dries it prevents the shrinkage of the same and it consists essentially of a heel member designed to fit into the heel of the stocking and a looped member designed to fit into the foot portion of the stocking, the members being adjustably connected together so as to fit any length of sock or stocking foot hereinafter more particularly explained by the following specification.

Figure 1, is a perspective view of my device showing the foot portion of the stocking in position thereon and in dotted lines. Fig. 2, is a cross section through the adjustable connection between the heel and foot portion of the device.

In the drawings like letters of reference indicate corresponding parts in each figure.

A is a plate curved up into the form shown so as to fit the heel of the sock or stocking and so as to form a handle A'.

B is a looped member fitting at the front the foot portion C of the sock or stocking C'. The looped member B extends rearwardly at each side and then curves inwardly at B' and then backwardly on itself so as to form a subsidiary loop B² located between the sides of the loop B. The loop B² forms a slot for a purpose which will hereinafter be described.

D is a clip provided with recesses D' designed to fit over the side member of the subsidiary loop B² and against the bottom of the plate A. The clip D is provided with a threaded stem D² extending through an orifice A² of the plate A.

D² is a butterfly nut threaded on the stem D² so as to draw up the clip D and clamp the sides of the loop B² against the plate A.

It will be readily seen that when it is desired to adjust my device to fit any length of stocking all that it is necessary to do is to 55 loosen the nut D² and slide the members A and B longitudinally of each other when the nut D² may be again tightened. My device is then inserted in the foot of the stocking when the stocking is in a wet state so that 60 the loop B extends into the foot thereof and the rear end of the plate A into the heel portion of the sock or stocking. The stocking is then dried my device preventing the shrinkage of the stocking during such dry- 65 ing process.

It will be readily seen that my device is simple and easily adjustable and is particularly adapted for ordinary household use where stockings often become useless 70 owing to their shrinkage to too small a size.

What I claim as my invention is:

1. A stocking stretching device comprising two members designed to fit the heel and foot portion of the stocking respectively, one of said parts comprising a substantially flat plate having a contracted forward end and a curved rear end and the other member comprising a loop having a contracted inner end, said inner end having 80 the side members thereof bent backward upon themselves to form a subsidiary loop extending between the main sides of the loop a substantial distance to form a longitudinal slot, and means on said plate engaging said slot to clamp the plate and loop together.

2. A stocking stretching device comprising a plate and loop member having a contracted inner end, the contracted sides of 90 the loop being turned backwardly of themselves so as to form a subsidiary slotted loop located between and parallel with the main sides of the loop, a clip designed to extend over suitable portions of the loop having 95 a threaded stem extending through the aforesaid plate and a butterfly nut threaded onto the stem, as and for the purpose specified.

ISAAC EDWARD YORK.
